UNITED STATES PATENT OFFICE.

WILLIAM CHARLES MOORE, OF NEW IBERIA, LOUISIANA.

CENTRIFUGAL MACHINE.

SPECIFICATION forming part of Letters Patent No. 584,046, dated June 8, 1897.

Application filed July 25, 1896. Serial No. 600,584. (No model.)

To all whom it may concern:

Be it known that I, WILLIAM CHARLES MOORE, a citizen of the United States, residing at New Iberia, in the parish of Iberia and State of Louisiana, have invented certain new and useful Improvements in Centrifugal Machines; and I do declare the following to be a full, clear, and exact description of the invention, such as will enable others skilled in the art to which it appertains to make and use the same.

My invention relates to improvements in centrifugal machines for separating molasses from sugar, and more particularly to the rotary baskets thereof; and it has for its general object to provide a rotary basket for a centrifugal machine embodying such a construction that the separation and escape of the molasses from the sugar will be materially accelerated, and in consequence the time necessary to separate each charge will be shortened and the capacity of the machine will be increased, and this without materially increasing the cost of the rotary basket.

Other objects and advantages of the invention will be fully understood from the following description and claims when taken in conjunction with the accompanying drawings, in which—

Figure 1 is a detail diametrical section of so much of a centrifugal liquid-separator as is necessary to illustrate my invention. Fig. 2 is an enlarged detail section showing my improvements. Fig. 3 is a view of the foraminated and sectional annulus of my improvements removed. Fig. 4 is an inverted plan view of the sectional block in which the guideways are formed. Figs. 5 and 6 are similar views of modified forms of block-sections. Fig. 7 is a detail perspective view of a block-section and one of the segments of the foraminated annulus connected together. Fig. 8 is an enlarged detail section illustrating a modification.

Referring by numerals to said drawings, and more particularly to Figs. 1 to 7 thereof, 1 indicates the casing of a centrifugal machine, which is designed to receive the molasses separated from the sugar and is provided with an outlet 2 for the same, and 3 indicates a central upright shaft, both of which may be and preferably are of the ordinary construction,

and 4 indicates the rotary basket, which is fixed to and is designed to turn with the shaft 3. This basket 4, like the ordinary basket, has the imperforate bottom 5, the inner and outer foraminated shells 6 and 7, and the interposed gauze 8, to permit the outward passage of molasses and retain the sugar, and the inwardly-directed annular portion 9, designed to prevent the sugar and molasses from being thrown out of the basket by centrifugal action.

As is well known to those experienced in operating centrifugal separators, the rapid rotation of the basket causes the wet sugar or "massquette" to distribute or spread itself evenly over the side wall of the basket, and when the sugar is of low grade the molasses will not pass through the sugar freely, but on the other hand often forms in a layer of varying thickness on the inner side of the sugar until gradually forced through the sugar into the casing 1. This prolongs the process of separation and materially reduces the capacity of the machine and is objectionable for that reason. The rapid rotation of the basket 4 also causes the sugar and the molasses to ascend the side of the same, and I propose to take advantage of such ascension of the sugar and molasses to accelerate the separation of the same and thereby reduce the time necessary to separate a charge and increase the capacity of the machine. To this end I provide the block 10 and the foraminated annulus or plate 11, and preferably connect gauze 13 to the under side of the plate 11. The block 10 may be in one piece or a plurality of segments, as shown in Fig. 4, and it is beveled on its upper side to conform to the inwardly-directed portion 9 of the basket 4, beneath which it is arranged and suitably secured, as illustrated. This block 10 is provided in its under side with grooves 12, which may be radially disposed, as shown in Figs. 1 to 4, tangentially disposed, as shown in Fig. 5, or curved, as shown in Fig. 6, and are preferably closed at their inner ends by a strip 14, increased in width toward their outer ends, as shown, so as to permit the molasses to flow more freely through such ends and thence out of the basket through the upper perforations in the outer shell 7. The foraminated annulus or plate 11 and the gauze 13, connected

thereto, may also be formed in segments arranged end to end, as shown, and it is arranged and suitably secured immediately below the grooved under side of the block 10, 15 and is designed and adapted to permit the molasses to pass to the grooves 12 of said block 10 and check the passage of the sugar, as will be hereinafter more fully explained.

The baskets of centrifugal machines at present in use have inwardly-directed portions 9 for the purpose before described, and the block 10 and annulus 11 are formed in segments, as described, in order that they may be readily placed and secured in the baskets. When, however, my improvements are embodied in a new machine, the block 10 and annulus 11 may be respectively formed in one piece. The block 10, when formed in one piece or of a plurality of segments, serves, in conjunction with the inwardly-directed portion 9 of the basket, to form an inwardly-directed flange 9^a, the grooves 12 in the block 10 being at the under side of said flange, as shown. When desirable, the inwardly-directed flange of the basket may be formed in one piece, as shown in Fig. 8. This flange 9^b is provided in its under side with grooves 12^a, which communicate at their outer ends with the upper perforations in the outer shell 7. 30 The foraminated annulus or plate 11 and the gauze 13, connected thereto, are also employed in conjunction with the flange 9^b, they being arranged and suitably secured immediately below the grooved under side of the flange, 35 as shown.

In the practical operation of the machine, when the charge of wet sugar is placed in the basket 4 and the said basket is rotated at a high rate of speed the sugar and molasses will be caused to ascend against the side of the basket, and the latter will take through the apertures of the plate 11, the grooves of the inwardly-directed flange, and the apertures of the shell 7, and into the casing 1, while 45 the sugar will be retained within the basket

by the plate 11. In virtue of this and the fact that a portion of the molasses will also be forced through the side of the basket it will be seen that a charge will be quickly separated, and that consequently the capacity 50 of the machine will be materially increased.

It will also be appreciated that my improvements are very simple and do not add materially to the cost of a centrifugal machine, and that the improvements may be added to 55 machines at present in use, as well as embodied in new machines.

Having described my invention, what I claim, and desire to secure by Letters Patent, is—

1. In a centrifugal machine for separating sugar and molasses a rotary basket or receptacle having a foraminous side, and an inwardly-directed flange, outwardly-extending grooves at the under side of the flange communicating at their outer ends with perforations in the foraminous side, and a foraminous plate at the under side of the flange covering the grooves, substantially as and for the purpose set forth.

2. In a centrifugal machine for separating sugar and molasses a rotary basket or receptacle having a foraminous side and also having an inwardly-directed portion at its upper end, a block arranged below the inwardly-directed portion and formed of segments and having grooves in its under side increased in width toward their outer ends and communicating at such outer ends with the foraminous side, and a foraminated plate also formed in segments and arranged at the under side of the block and covering the grooves therein, substantially as and for the purpose set forth.

In testimony whereof I affix my signature in presence of two witnesses:

WILLIAM CHARLES MOORE.
